[57]

ABSTRACT

A hand tool usable for gripping pipes or other objects comprises an opposed pair of jaws pivoted on integral extensions at a point remote from the jaws. One jaw pivotably mounts an elongated handle with pawl means at the pivoted end thereof. A leaf chain extends from the handle, over the pawl means to the opposite jaw where it is pivotably anchored. The handle may be selectively pivoted to engage the chain with the pawl means, thereby forcing the jaws together, or to disengage the pawl means from the chain, thereby facilitating free movement of the jaws together or apart.

PIPE GRIPPING TOOL

BACKGROUND OF THE INVENTION

The present invention relates to tools having jaws positioned by relatively movable plural handles and more particularly to such tools utilized to manually grip items so they can be released simply by releasing the manual grip.

It is often desirable to utilize a tool which provides integral means for tightly gripping an object without requiring the same amount of exertion by the user. It is further desirable to utilize such a tool which also provides means for easily and quickly adjusting the distance between the gripping jaws.

A search of prior art has revealed the following relative United States patents of interest:

U.S. Pat. No. 3,618,431 granted to R. B. Nockleby;
U.S. Pat. No. 3,566,721 granted to R. B. Nockleby;
U.S. Pat. No. 2,932,226 granted to A. Sepolla; U.S. Pat. No. 639,812 granted to T. Jensen.

The first two patents cited above granted to me on Nov. 9, 1971 and Mar. 2, 1971 respectively are similar to the present invention only in that both include an opposed set of jaws, each having an extension thereon with the extensions being hinged to each other at a point remote from the jaws.

The Sepolla patent shows a pipe wrench using a flexible chain as the gripping element. The apparatus does not show rigid jaws that are movably positioned by means of a chain which acts as a positioning and tensioning member during gripping of an object between rigid jaws.

The T. Jensen patent discloses a monkey wrench having an adjustable pivot and including three handles. The pivot is adjustable by means of a threaded shaft and a knob threadably engaged thereon.

The apparatus of the present invention comprises a rigid pair of jaws each having an extension thereon and hinged to each other at a point remote from the jaws. An elongated handle is pivotably mounted to one of the jaws. A flexible linkage is anchored to the opposite jaw and extends through an opening in the one jaw to the handle. The handle includes means for engaging the linkage and applying a levered force to it, thereby pulling the jaws relatively together. This levered force is applied as the handle is pivoted toward the hinged extensions. By pivoting the handle away from the hinged extensions, the linkage is disengaged from the handle, thereby allowing free adjusting movement of the jaws relative to one another.

SUMMARY OF THE INVENTION

The apparatus disclosed herein comprises a hand tool having opposed jaws and extensions on the jaws which are hinged to each other at a point remote from the jaws. An elongated handle is pivotably mounted at one end thereof to one of the jaws, the pivot axes for said extensions and said handle being parallel.

A flexible linkage is anchored at one end to the remaining jaw and is connected by means of a tension spring to the handle. The handle includes pawl means at one end thereof for releasably engaging the linkage to pull the anchored end and thereby the jaws together.

It is a first object of my invention to provide a hand tool which has more gripping leverage than a regular plier-type tool.

It is a further object of my invention to provide such a tool that is compact and yet can effectively be used on large objects.

It is a further object to provide such a tool wherein the gripping leverage may be easily released thereby enabling the tool to be used in ratchet fashion.

These and further objects and advantages will become evident upon reading the following disclosure with reference to the attached drawings.

A BRIEF DESCRIPTION OF THE DRAWINGS

FIG. 1 is a side elevational view of the tool showing portions thereof broken away;

FIG. 2 is a plan view of the apparatus shown in FIG. 1;

FIG. 3 is a view similar to FIG. 1, only showing the tool in an operative position with an object shown in phantom lines between the jaws;

FIG. 4 is a fragmentary view showing an inoperative position of the handle;

FIG. 5 is a fragmentary isometric view of a portion of the tool handle;

FIG. 6 is a fragmentary elevational view of the hinged end of the extension with an extension formed thereon; and

FIG. 7 is a fragmentary elevational view of the hinged end of the handle with an integral extension formed thereon.

DESCRIPTION OF A PREFERRED EMBODIMENT

Referring now to the drawings in greater detail, and especially to FIGS. 1 and 3, there is shown a preferred form of the invention basically comprising an opposed pair of jaws 10 and 11 having a pair of extensions 12 and 13 respectively extending outwardly therefrom. Extensions 12 and 13 are hinged together at a point remote from the jaws for pivotal movement about an axis defined by a hinge pin 14.

The jaws are longitudinally concave to conform to objects such as the pipe 15 shown in FIG. 3 by phantom lines. The shape of the jaws, however is not intended to be restricted to such shapes nor is utilization of the tool to be restricted to specific work pieces. Pipe 15 is exemplary of only one specific work piece that I have found to be easily workable with the present invention.

An elongated handle 16 is pivotally mounted to a forward end 17 of extension 12 by means of a pivot pin 18, the axis of which is parallel to the axis defined by hinge pin 14. Pivot pin 18 provides a lever fulcrum for the gripping action of the jaws 10 and 11 which will be discussed in greater detail below.

Handle 16 is mounted within an opening 20 extending vertically through the forward end 17 of extension 12. Opening 20 is longitudinally elongated to allow free pivotal movement of the handle relative to extension 12 between the positions shown in FIGS. 1 and 4. Handle 16 is operatively connected to extension 13 adjacent jaw 11 by a flexible linkage comprised of a conventional leaf chain 22 and a tension spring 25.

Chain 22 includes a plurality of links 19 pivoted end to end by pins 21 which extend outwardly from the link sides as shown in FIG. 2. The chain is connected at one end to extension 13 by a pivot pin 23. The end link 19 and end 23 fit within a recess (not shown) in extension

13 which allows pivotal movement of that link about an axis parallel to the axes of pins 14 and 18.

Chain 22 extends upwardly from pin 23 through opening 20 and along a guide channel 24 which is formed as an integral part of handle 17. The other end of chain 22 is connected to one end of spring 25 which extends therefrom to an outer end 29 where it is anchored to a downwardly protruding lip 28.

Spring 25 is utilized to urge the chain toward a straight line between pin 23 and anchor lip 28 on handle 16. This condition is prevented, when the handle is in a gripping position, by a pawl means at a vertically open inner end 30 of handle 16.

The open end 30 of handle 16 is defined by transversely spaced vertical wall sections 30a and 30b. The wall sections are spaced apart a distance sufficient to allow free passage of the chain links therebetween, but insufficient to allow passage of the pins 21, which must slide over the top wall edges.

The pawl means is formed in the wall sections along the top edges and comprises two sets of transversely aligned recesses, 31 and 36 respectively for engaging the pins 21. The recesses are formed as semi-circles including not more than 180° with their transverse axes equally spaced from pivot pin 18 and parallel to the center axes of the chain link pins 21. The distance between the axes of recesses 31 and 36 is less than the distance between axes of adjacent chain link pins 21. By spacing the recesses as such, the pawl means is assured of engaging a pin within one or the other set of recesses with a minimal amount of movement of the handle 16 toward a closed position, regardless of the relative position of the chain link pins 21. This feature may best be understood with reference to FIG. 4 wherein a pin 21a is shown in the pivotal path of recesses 36. If, however, the size of the object 15 necessitated that the jaws be spaced apart with the pin 21a positioned between recesses 36, 31, the pin would then lie in the pivotal path of recesses 31 and would be engaged thereby (as shown in FIGS. 1, 2, and 5) following approximately the same amount of handle movement required as described to engage pin 21a in recesses 36 as shown in FIG. 4.

FIG. 4 partially illustrates the tool in an inoperative position wherein the chain is disengaged from the pawl means and is thus extendible relative to handle 16, by expanding the spring 25. Such disengagement of the pawl means from the chain frees the jaws for pivotal movement about the axis of hinge pin 14. Such free movement facilitates positioning of the jaws relative to one another sufficiently apart to allow an object to be received therebetween.

Once the jaws are positioned on either side of an object, as shown in FIG. 3, the handle may be pivoted toward extension 12 to engage a pin 21 in recesses 31 or 36. Further pivotal movement of the handle in this direction creates a tensile force on the length of chain between the pin 21 engaged by recesses and the pin 23 which mounts the end of the chain to extension 13. This force serves to pull the jaws 10 and 11 together, thereby clamping the object. It may be noted that the distance between pin 18 and recesses 31, 36 is substantially less than the distance between the pin 18 and the outer end 29 of handle 16. With pin 18 acting as a fulcrum, these relative distances define a substantially efficient lever which is utilized to pull jaws 10 and 11 together thereby tightly clamping an object such as the pipe 15. The handle 16 may be provided with an exten-

sion 34 as shown in FIG. 7, and extension 13 may be provided with an additional extension 33 as shown in FIG. 6, which together will improve the leverage against chain 25 to provide even greater gripping force to jaws 10 and 11.

As may be noted in FIG. 3, the chain may be deflected by the periphery of the object when gripped. This feature is advantageous in two ways. Firstly, the tension on the chain during gripping action creates an additional grip force which is offset from the opposed forces of the jaws. Secondly, the chain provides an additional surface in contact with the object and therefore aids to prevent slipping of the jaws on the object.

Also shown in FIG. 6 is a torsion spring 35 loosely fitted around hinge pin 14 with its ends in contact with extensions 12, 13 as shown. Spring 35 may be used to bias the extensions 12, 13 and thereby jaws 10, 11 apart with handle 16 in the inoperative position shown in FIG. 4 thereby equalizing or overcoming the tensile force of spring 25 which normally would urge the jaws 10 and 11 together.

Operation of the tool may now be easily understood with reference to FIGS. 1, 3 and 4. To first grip an object, the operator pivots the handle 16 to the position shown in FIG. 4, thereby disengaging the chain 22 from the notches 31. The jaws 10 and 11 are thereby free to pivot about the axis of hinge pin 14 together or apart a distance slightly greater than the size of the object to be gripped. Once the object has been received between the jaws 10 and 11, the handle 16 may again be pivoted toward the extensions 12 and 13 pivoting the pawl means to engage a pin 21 of the chain 22. Further force on the handle 16 toward the extensions then forceably pulls the jaws together against the object. To release the object, the operator simply allows handle 16 to return to a normal position thereby relaxing the gripping force on the jaws.

By providing such a simple, yet efficient gripping means, I have found that the tool may be used ratchet style by first gripping the object and twisting it, releasing the handle, then regripping the object and twisting again.

It may be obvious that various changes and modifications may be made with respect to the above description and attached drawing. Therefore, only the following claims are intended to define this invention.

What I claim is:

1. A hand tool usable to grip items by hand action, comprising:
a first jaw;
a second jaw opposing said first jaw;
a first extension on said first jaw;
a second extension on said second jaw, said first and second extensions being hinged to each other at a point remote from the jaws;
an elongated handle pivotably mounted at one end thereof to said second extension adjacent said jaw, the pivot axes for said extensions and said handle being parallel;
flexible non-extensible linkage anchored at one end to said first extension adjacent said first jaw;
a tension spring connected at one end to said linkage and at the other end to said handle adjacent an end thereof opposite said one end;
pawl means at said one end of said handle, integral therewith and radially spaced from said pivot axis

and operative by application of inward force on said handle relative to said extensions to releasably engage said linkage and pull said anchored end, and thereby said first jaw, toward said second jaw;

said pawl means being spaced radially from the pivot axis of said handle to provide a lever arm thereby multiplying said inward force on said jaws.

2. The tool defined in claim 1 further including means for mounting said handle for pivotable movement between:

a first position wherein said pawl is disengaged from said flexible linkage, thereby facilitating free movement of said jaws together or apart, the amount of such movement being restricted only by the length of said flexible linkage and expanded length of said tension spring; and

a second position wherein said pawl is engaged with said flexible linkage, thereby limiting the jaws to relative movement in response only to pivotal movement of said handle.

3. The tool defined in claim 1 wherein said flexible linkage comprises a conventional flat link pitch chain including a plurality of flat links pivotably held end to end by a plurality of transverse pins;

and wherein said pawl comprises at least one open recess formed within said one end of said handle complementary in configuration to said transverse

10

15

20

pins and adapted to receive a pin therein; said recess being radially spaced from the pivot axis of said handle at a point between said axis and said second jaw.

4. The tool defined in claim 1 wherein said flexible linkage comprises a conventional flat link pitch chain including a plurality of flat links pivotably held end to end by a plurality of transverse pins having ends protruding transversely outward from the links;

said handle further including transverse spaced wall sections integral with said handle at said one end, the wall sections being spaced apart a distance greater than the transverse thickness of said chain links and equal to or less than the distance between the ends of said transverse pins;

said wall sections having top edge surfaces radially spaced from the pivot axis of said handle; paired sets of recesses complementary in configuration to said pins formed in said top edge surfaces along axes parallel to said pins and equidistant from the pivot axis of the handle, adapted to selectively receive and release said pins in response to pivotal movement of said handle.

5. The tool defined in claim 4 wherein the axes of the recesses are spaced apart a distance less than the distance between successive pins of said chain.
